UNITED STATES PATENT OFFICE

MOE SHENKIN, OF NEW YORK, N. Y.

DESIGN FOR A CIGARETTE DISPENSER OR SIMILAR ARTICLE

Application filed December 4, 1929. Serial No. 33,646. Term of patent 7 years.

To all whom it may concern:

Be it known that I, MOE SHENKIN, a citizen of the United States, residing at 135 Grand St., New York, N. Y., have invented a new, original, and ornamental design for a Cigarette Dispenser or Similar Article, of which the following is a specification, reference being had to the accompanying drawing, forming part thereof.

The single figure is a perspective view of the cigarette dispenser, showing my new design.

What I claim is:

The ornamental design for a cigarette dispenser or similar article, substantially as shown.

MOE SHENKIN.
